UNITED STATES PATENT OFFICE.

WILLIAM F. LUTZ, JR., OF BROOKLYN, NEW YORK.

CHANGEABLE KNIFE-HANDLE.

1,202,299.

Specification of Letters Patent. Patented Oct. 24, 1916.

Application filed August 6, 1915. Serial No. 43,948.

To all whom it may concern:

Be it known that I, WILLIAM F. LUTZ, Jr., a citizen of the United States, and residing at Brooklyn, in the county of Kings and State of New York, have invented certain new and useful Improvements in Changeable Knife-Handles, of which the following is a specification, such as will enable those skilled in the art to which it appertains to make and use the same.

This invention relates to butchers' knives, carving knives and other knives of this class, and the object thereof is to provide a knife of this class with a detachable handle, or in which the handle may be detached from the blade whenever desired, and a new blade substituted for an old one, or a broken one, and with this and other objects in view, the invention consists in a device or devices of the class specified, constructed as herein-after described and claimed.

The invention is fully disclosed in the following specification, of which the accompanying drawing forms a part, in which the separate parts of my improvement are designated by suitable reference characters in each of the views, and in which:—

Figure 1 is a side view of a knife, the handle of which is made according to my invention; Fig. 2 a longitudinal section on the line 2—2 of Fig. 1; Fig. 3 a similar section on the line 3—3 of Fig. 1; Fig. 4 a view showing the handle open with the blades detached; and Fig. 5 a view of the shank portion of the blade.

In the practice of my invention, I provide a knife blade handle *a* of the usual general form, but divided centrally and longitudinally, and in the plane of the blade into two separate parts *a*² and *a*³, hinged together at *a*⁴, and the parts *a*² and *a*³ consist of outer block members *a*⁵, and inner plate members *a*⁶ and *a*⁷ and said inner plate members *a*⁶ and *a*⁷ are provided in their inner faces with depressed spaces *a*⁸, provided with projecting circular members *a*⁹, and the spaces *a*⁸ are of the form shown in Fig. 4, and are adapted to receive the shank portion *b* of a blade *b*² which is flat in form and provided with circular apertures *b*³ adapted to receive the circular projections *a*⁹. The block members *a*⁵ of the handle are secured to the inner plate members *a*⁶ and *a*⁷ by rivets *a*¹⁰, and the plate member *a*⁶ is provided at the free edge portion thereof with lock devices *c*, formed

from said plate member *a*⁶, as indicated by the cut out portion *c*², and said lock devices are arranged at right angles to said plate member *a*⁶, and said lock devices *c* are also provided with backwardly directed projections *c*³, and the plate member *a*⁷ is provided with slots *d*, arranged at the free edge portion of said plate and in line with the lock devices *c*, and through which said devices are adapted to pass, and between said slots *d* is formed a projecting member *d*², cut from the material of said plate member *a*⁷, and which is adapted to prevent the outward movement of a lock plate *e*, provided with a finger piece *e*², and the lock plate *e* is provided with two slots or recesses *e*³, through which the lock devices *c* are adapted to pass, and between said slots *e*³ is arranged another slot *e*⁴, in which the projecting member *d*² is adapted to operate.

In attaching a knife blade similar to that shown in Fig. 5 to the handle, the shank portion *b* thereof is placed in one of the depressed spaces *a*⁸ in one of the plate members of one part of the handle, after which the other part of the handle with the plate member is swung over and on top of the said shank portion of the knife blade, the lock plate *e* being first extended into the position shown in dotted lines in Fig. 3, to permit the lock devices *c* to pass freely through the apertures *d* and *e*³, after which the said lock plate *e* is forced inwardly into the position shown in full lines in Fig. 3, in which position the edge portion of the slots *e*³, adjacent to the projecting members *c*³, pass over said projecting members as clearly shown in said figure, and prevent the separation of the separate parts of the handle member *a*, and it will be understood that in order to detach the knife blade *b*² from the handle member *a*, the lock plate *e* is withdrawn from its full line position, into the position shown in dotted lines in Fig. 3, in which position the lock devices *c* are free to pass through the slots *e*³ and *d*.

By means of my improvement, I provide a knife of the class specified, with a detachable handle, whereby a new blade may be substituted for an old one, or a broken one, whenever desired, and while I have shown and described the preferred form of my improvement, my invention is not limited to the exact details of construction herein shown and described, and changes therein

and modifications thereof may be made within the scope of the appended claims, without departing from the spirit of my invention or sacrificing its advantages.

5 Having fully described my invention, what I claim as new and desire to secure by Letters Patent, is:—

10 1. A knife of the class described, comprising a handle and a blade, the handle being composed of separate parts hinged together at one side and said parts being provided on their inner sides with plates having longitudinal recesses forming a chamber which opens through the blade end of the handle and the 15 blade being provided with a shank which is placed in one of said recesses when the separate parts of the handle are open, and said handle being also provided with a longitudinally movable locking slide which operates in connection with the said plates and whereby the separate parts of the handle are 20 locked together, and said plates being also provided in said recesses with raised members which fit in corresponding apertures in the shank of the handle.

25 2. A knife of the class described comprising

Copies of this patent may be obtained for five cents each, by addressing the "Commissioner of Patents, Washington, D. C."

ing a handle and a blade, the handle being composed of separate parts hinged together at one side and said parts being provided on their inner sides with plates having longitudinal recesses forming a longitudinal chamber which opens through the blade end of the handle and the blade being provided with a shank which is placed in one of said recesses when the separate parts of the handle are open, one of said plates being provided with apertures and the other with locking devices which pass through said apertures, and said handle being also provided with a longitudinally movable locking slide through which said locking devices also pass and by which the separate parts of the handle are locked together.

30 In testimony that I claim the foregoing as my invention I have signed my name in 35 presence of the subscribing witnesses this 4th day of August, 1915.

WILLIAM F. LUTZ, JR.
